(57) CLAIM

The ornamental design for an electronic musical instrument, as shown and described.

DESCRIPTION

FIG. 1 is a first perspective view of an electronic musical instrument showing our new design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The dot-dashed broken line showing in the views represent boundaries of the claim and forms no part of the claimed design. The dashed line portions of the electronic musical instrument in the views represent unclaimed portions of the claimed design and form no part thereof.

1 Claim, 7 Drawing Sheets
